[57] **CLAIM**

The ornamental design for a wall mounted plate rack, as
shown and described.

DESCRIPTION

FIG. 1 is a front elevational view of a wall mounted
plate rack showing my new design;

FIG. 2 is a front perspective view thereof;

FIG. 3 is a left side elevational view, the right side being
a mirror image thereof; and

FIG. 4 is a top plan view thereof.

FIG. 4

FIG. 1

FIG. 3

FIG. 2
